UNITED STATES PATENT OFFICE.

JAMES WILLIAM MITCHELL, OF NEW DECATUR, ALABAMA, ASSIGNOR OF ONE-HALF
TO JAMES MADISON WATSON, OF NEW DECATUR, ALABAMA.

ANDIRON.

1,070,162.

Specification of Letters Patent.

Patented Aug. 12, 1913.

Application filed January 29, 1913. Serial No. 744,963.

To all whom it may concern:

Be it known that I, JAMES W. MITCHELL, a citizen of the United States, residing at New Decatur, in the county of Morgan and

5 State of Alabama, have invented a new and useful Andiron, of which the following is a specification.

This invention relates to improvements in andirons, the object being to provide an 10 andiron of neat appearance and with fuel holding supports which may be held in adjusted positions at various distances apart, to thereby accommodate fuel of different lengths.

15 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

25 In the drawings accompanying this specification and forming a part thereof, the preferable form of my invention is illustrated, in which:—

Figure 1 is a view in perspective of my 30 improved andiron. Fig. 2 is a transverse cross sectional view thereof taken on the line 2—2 of Fig. 1.

Referring to the drawings in which similar reference numerals designate corresponding parts throughout the several views, 1 represents the upper longitudinal bar and 2 the lower one of the front frame A. The 35 said lower bar 2 is suitably connected to the bar 1 by means of the uprights 3, 4 and 5, the upright posts 3 and 5 being provided 40 with the downwardly extending portions 6 and 7 which constitute supporting legs for the frame. The bar 1 is provided with triangular projections upon its upper surface 45 designated as 8 and the lower bar 2 is provided with a number of cylindrical studs or projections 9, the last mentioned studs or cylindrical projections being in vertical alinement with the triangular projections 50 of the upper bar.

The fuel supports are detachably secured to the frame A and comprise the horizontal body portions 10 one end of which is bent downward in order to form the depending 55 legs 11. The other end of the body por-

tions 10 is bent upward as at 12 and is provided with the spaced lugs 13 and 14 which are adapted to engage the bars 1 and 2 respectively of the frame A.

In order that the andirons may present a 60 neat attractive and pleasing appearance, the upright members 3, 4 and 5 are provided with the extensions 15 and the serrated edges 16.

The spaced lugs 13 and 14 which are preferably formed integral with the upstanding portions 12 of the fuel holding supports are adapted to engage the upper and lower longitudinal bars 1 and 2 respectively of the frame A and be detachably secured thereto. 65 By the providing of these bars with the plurality of projections and cylindrical studs, the fuel holding supports may be held in adjusted position at various distances apart thereby accommodating fuel of different 70 lengths.

The cylindrical studs upon the lower bar of the frame lend a neat and attractive appearance to the frame and acting in conjunction with the upper triangular projections 75 prevent the shifting of the fuel holding supports and maintain the same in a substantially vertical plane, it also being pointed out that the projecting studs prevent the fuel supports from tilting.

Having thus fully disclosed the construction of my improved andiron, what I claim to be new and original with me is:—

1. An andiron comprising a frame, having projections extending upwardly and 90 studs extending outwardly therefrom, said frame provided with legs at the extremities thereof, fuel supports comprising horizontal body portions, one end thereof bent downward to form a supporting leg, the other end 95 of said body portion bent upward and provided with spaced lugs, said lugs adapted to engage the upper and lower portion of said frame, and fitting between the said studs, said studs adapted to prevent the tilting of the fuel holding supports and to maintain the same in a vertical adjusted position. 100

2. In an andiron the combination of a frame with upper and lower longitudinal bars, said upper bar provided with triangular projections extending upwardly therefrom, said lower bar provided with cylindrical studs extending outwardly therefrom, and said frame provided with legs formed integral with the said longitudinal bars at 110

the extremities thereof, and fuel supports comprising horizontal body portions, one end of said body portions bent downward to form a supporting leg, and the other end of 5 said body portions bent upwardly and provided with spaced lugs, the said spaced lugs extending between the said triangular projections and said cylindrical studs and held in adjusted position thereby, said cylindrical

studs preventing the tilting of the fuel sup- 10 porting members.

In testimony that I claim the foregoing as my own, I have hereto affixed my signature in the presence of two witnesses.

JAMES WILLIAM MITCHELL.
